UNITED STATES PATENT OFFICE.

HIRAM S. MAXIM, OF BROOKLYN, NEW YORK.

MECHANISM FOR OPERATING GUN-LOCKS BY RECOIL.

SPECIFICATION forming part of Letters Patent No. 297,278, dated April 22, 1884.

Application filed June 30, 1883. (No model.)

To all whom it may concern:

Be it known that I, HIRAM S. MAXIM, a citizen of the United States, and resident of Brooklyn, Kings county, State of New York, residing temporarily at Paris, in the Republic of France, have invented certain new and useful Improvements in Fire-Arms; and I do hereby declare the following to be a full, clear, and exact description of the invention, such as will enable others skilled in the art to which it appertains to make and use the same.

My invention relates to fire-arms of the class usually called "repeating rifles," of which the Winchester breech-loading rifle may be considered a type.

It consists of a device for utilizing the kick of such rifles for operating the breech-loading mechanism, and is constructed in such a manner that when the rifle is discharged the rebound stores up sufficient energy in two spiral springs to operate the necessary mechanism for extracting the exploded shell of the cartridge, for cocking the instrument, for placing a new cartridge in position, forcing it into the barrel, and closing the breech.

It is well known that heavy-loaded rifles such as are used for military purposes rebound with great force and often do injury to the shoulder of the person firing them. By my device a yielding shoulder-piece diminishes the force of the kick or rebound, and at the same time stores up sufficient energy to prepare the rifle for the next succeeding shot.

In the drawings a rifle of the Winchester type is shown, and the parts not illustrated will be understood to be the same as in said well-known rifle. The apparatus will, however, operate equally well on any arm of the kind, or upon a revolver.

Figures 1 and 2 of the drawings are views, partly in side elevation and partly in section, of a portion of a gun provided with my improvements, these figures, respectively, showing the operative mechanism in different positions.

The left-hand portion of the drawings is in section, and shows the apparatus in the position to be ready for firing. On discharging the rifle, the plate C being firmly placed

against the shoulder, the rebound will compress the two spiral springs J and K. At the same time the latch G will be thrown, when the spring L will cause the notch b to engage the catch H. This will hold both the springs in a compressed state. When, however, the force of the discharge has been expended and the lever F is free to move, the force of the spring J will press the bolt D forward until the center e reaches f, and the point d reaches the point e. This movement cocks the instrument and throws out the old shell. As soon, however, as the wheel I has advanced to a proper point, it will have lifted the latch G from the catch H, when the spring K will move all the parts back into the position shown in the drawings. This movement, of course, finishes the operation of making the instrument ready for firing again. Upon discharging the rifle the guard E acts as a connecting-rod between the points e and d. At each firing the point O strikes the trigger N at R and liberates the little pin P, which is connected to the spring which carries the sear, acting as a stop or arrester of the trigger, as in the Winchester rifle, heretofore referred to. The trigger is thus brought back into its first position at each discharge, and the trigger cannot again be drawn until the little pin P is again compressed.

It will be obvious that a rifle provided with this device will be susceptible of being fired with great accuracy and rapidity.

As repeating rifles are now made, some movement on the part of the operator is necessary to reload. The movement, although slight, requires time and destroys the aim, whereas a heavy-loaded rifle, from its rebounding force, is another cause operating against accuracy and rapid firing. With this instrument, however, the operator has nothing to do except to pull the trigger at each discharge or to press steadily upon the trigger, when the full contents of the magazine will be rapidly discharged, while the yielding plate C relieves the shoulder from the force of the discharge.

I am aware that a movable spring-supported shoulder-plate has been applied to the stock

of a gun and connected with the hammer in such manner as to cock the same when the said shoulder-plate is forced up to the butt of the stock, and I do not claim such combination, broadly.

5 What I claim is—

1. The combination, with the gun-stock and hammer-operating lever F, of the bolt D, arranged in a passage in the stock, the rod E, connecting said bolt with said hammer-operating lever, the shoulder-plate C, supported by a suitable guide, the spring J, having one end bearing against said plate and the other against the end of bolt D, a spring arranged 10 to force said bolt in opposition to said spring J, a latch for holding plate C compressed to the butt of the stock, and a device operated by the kick or rebound of the gun for releasing said latch, substantially as described.
2. The combination, with the hammer-operating lever F, trigger N, and pin P, connected with the trigger-stop, of the shoulder-plate C, the latch G, connected thereto, the stationary catch H, the bolt D, carrying a trip 15 for releasing said latch, the spring J, arranged 20

between the bolt and shoulder-piece, spring K, arranged to drive the bolt rearwardly, and the combined guard and connecting-rod E, pivoted at its front end to the trigger-operating lever and at its rear end to the bolt, and 25 provided intermediately with the projection O, arranged to strike the rear side of the trigger when the rod is thrown forward and to press inward the trigger stop-pin when it is drawn rearward, the whole arranged, as shown, 30 in connection with the stock of a gun of the kind described.

3. The combination, with the movable shoulder-plate C, connected with the hammer-cocking lever of a gun, as described, of a latch arranged to hold said shoulder-plate to the position for cocking the hammer, and a device operated by the rebound of the gun for unlatching said plate, substantially as described.

In witness whereof I have hereunto subscribed my name.

HIRAM S. MAXIM.

In presence of—
EDWARD P. MACLEAN,
J. S. J. EATON.
